FRANK CLEWLEY, OF PHILADELPHIA, PENNSYLVANIA, ASSIGNEE TO SIMON FRIEDBERGER, OF PHILADELPHIA, PENNSYLVANIA.

TWISTED-NET FABRIC.

1,139,344.

Specification of Letters Patent.

Patented May 11, 1915.

Application filed November 18, 1914. Serial No. 872,695.

To all whom it may concern:

Be it known that I, FRANK CLEWLEY, a citizen of the United States, residing at Philadelphia, county of Philadelphia, and 5 State of Pennsylvania, have invented a new and useful Improvement in Twisted - Net Fabric, of which the following is a full, clear, and exact description, reference being had to the accompanying drawings, which 10 form a part of this specification.

The object of my invention is to provide a new and improved open work knitted fabric especially adapted for use in the manufacture of laundry bags and dyers' bags. 15 Such bags are subjected to hard wear and are sometimes cut or torn at different points. It is important, therefore, that they should be so knitted that if so torn or cut the damage will be localized. This necessitates the 20 knitting of the fabric in such manner that the threads of which the fabric is knitted shall be interlocked at very frequent intervals in the knitting operation so that it will be absolutely impossible to ravel any particular thread or chain beyond a very small distance.

The fabric may be knitted on a rib-lace machine in which only two guide bars, carrying two sets of needles, manipulating two 30 sets of thread, are rendered operative. Two threads, one of one set and one of another set, are manipulated together as a pair and caused to interloop to form chains extending longitudinally or in the direction in which 35 the fabric is knitted. Any given chain, however, is formed partly of the threads of one pair and partly of the threads of another pair; this being effected by causing the threads of a given pair, after they have 40 been interlooped to form a series of loops of one chain, to be diverted laterally and then interlooped to form a series of loops of another chain, after which they are diverted laterally in the opposite direction, and then 45 interlooped to form another series of loops of the first chain, and so on. Between the first and last named series of loops of the first chain is an intermediate series of loops formed by another pair of threads. At the 50 junction between two series of loops of the same chain, one of the threads of the pair forming one of said two series of loops is loo - around one of the threads of the pair forming the other of said two series of loops

loops, thus tying together the two series of 55 loops.

In the preferred form of my invention, one thread of each pair, which I call the locking thread, always performs the looping function, while the other thread of the 60 pair, which I call the locked thread, is the thread which is confined by the loop of the locking thread of another pair; the locked thread at this point being itself formed into a loop through which extends the lock- 65 ing thread of the last named pair in its transverse extension toward the adjacent chain. Thereby the threads are interlocked at this point in such manner that accidental raveling is impossible in the event of break- 70 age of any of the threads adjacent thereto.

The construction will be better understood by reference to the accompanying drawings showing a preferred form of my invention, in which—

Figure 1 is an enlarged face view of the fabric in which, however, the fabric is distorted to show the longitudinal rows of loops extending in a straight line and to accentuate the open-work effect. Fig. 2 is a 30 face view showing more accurately the appearance of the fabric to the eye.

x , y , z , represent three adjacent longitudinally extending chains.

a , b , represent respectively the locking 35 thread and locked thread of one pair of threads. a' , b' , represent respectively the locking thread and locked thread of another pair of threads.

It will be understood that the terms 90 "locking" and "locked" are employed somewhat arbitrarily, the fact being that the connection between these two threads is more in the nature of an interlocking connection.

It will be observed that threads a and b are interlooped to form a series of loops in the chain x , thence extend transversely and form a series of loops in the chain y , and thence extend transversely to form another 100 series of loops in the chain x ; and so on. Threads a' and b' are interlooped to form a series of loops in the chain y , thence extend transversely and form a series of loops in the chain z , and thence extend transversely and form another series of loops in the chain y , and so on. Thus, the chain y is formed of a number of series of loops 105

formed by threads a' and b' alternating with a number of series of loops formed by threads a and b . The other chains are similarly formed partly of loops formed by one 5 pair of threads and partly of loops formed by another pair of threads.

It will be observed, by reference to (say) the lower part of the section of chain y shown in the drawings, that thread a' is 10 formed into a loop which extends around thread b at two points in its length; or more specifically, thread a' is formed into a loop 1 which extends around the neck of a loop 2 formed by thread b . The loop 2 formed by 15 thread b is interlooped with a loop 3 formed by thread a , which latter thread also extends through loop 2 formed by thread b and thence extends together with thread b transversely toward the chain x . The said 20 loop 3 formed by thread a extends around the neck of a loop 4 formed by thread b , which loop 4 in turn extends around the neck of a fifth loop 5 formed by thread a ; threads a and b thence extending transversely toward the chain x .

The said fifth loop formed by thread a corresponds to said first loop formed by thread a' , and engages thread b' in the same manner as thread a' is above described as 30 engaging thread b . It will thus be understood that I have described a complete single "repeat" of the fabric along the line of a single chain, including its connection with adjacent repeats, which will suffice for an 35 understanding of the entire fabric.

After the fabric is knitted the fabric tends to assume the form shown in Fig. 2; that is, the tying-in loops of threads a , a' , etc., tend to draw out and elongate in a lateral direction owing to the "pull" between each series 40 of loops in one chain and the two series of loops formed by the same pair of threads in an adjacent chain. This produces irregular but similarly shaped rows of figures, the 45 figures of each row being alternately staggered to the right and left.

It will be observed also that the threads are twisted one upon another, thereby producing a stronger fabric.

Having now fully described my invention, what I claim and desire to protect by Letters Patent is:

1. A knitted fabric composed of a number of longitudinally extending chains each 55 of which is composed of alternating series of loops, the loops of one series of one chain being integrally united with the loops of a series of another chain and being interlocked with the loops of the adjacent series of the 60 first chain.

2. A knitted fabric composed of a number of longitudinally extending chains each of which is composed of alternate series of loops, one pair of threads forming the loops 65 of one series and another pair of threads

forming the loops of another series, the loops of one series of one chain being interlocked with the loops of the adjacent series of the same chain, and the pair of threads composing each of said series of loops extending to, and forming a series of loops of, another chain. 70

3. A knitted fabric composed of a number of pairs of threads forming longitudinally extending chains, each of which is composed of knitted loops adjacent series of which are formed of two different pairs of threads, each pair of threads at the junction between adjacent series of loops of the same chain being interlocked with the other pair of threads and thence extending transversely to, interlocking with, and forming part of, another chain of loops. 75

4. A knitted fabric composed of a number of pairs of threads, the threads of one pair being interlooped to form a section of a chain, thence extending transversely and interlooped to form a section of another chain, thence extending transversely and interlooped to form another section of the first 80 chain, the threads of another pair being interlooped to form a section of the first chain connecting the other specified section of the first chain and extending transversely and interlooped to form discontinuous sections of 85 a third chain. 90

5. A knitted fabric composed of a number of pairs of threads, the threads of one pair being interlooped to form a section of a chain, thence extending transversely and interlooped to form a section of another chain, thence extending transversely and interlooped to form another section of the first chain, the threads of another pair being interlooped to form a section of the first chain 100 between the other specified sections of the first chain, the said intermediate section being interlocked with the other sections of the first chain. 105

6. A knitted fabric composed of a number of pairs of threads forming longitudinally extending chains, each of which is composed of knitted loops adjacent series of which are formed of two different pairs of threads, one thread of each pair, at the junction between adjacent series of loops of the same chain, being looped around one thread of said adjacent series and thence, together with the other thread of the same pair, extending transversely and forming a series of 110 loops of another chain. 115

7. A knitted fabric composed of a number of pairs of threads, the threads of one pair being interlooped to form a section of a chain, thence extending transversely and interlooped to form a section of another chain, thence extending transversely and interlooped to form another section of the first chain, the threads of another pair being interlooped to form a section of the first chain 125 130

between the other specified sections of the first chain, one thread of each section of a chain being looped around the loop formed by one thread of an adjacent section of the 5 same chain.

8. A knitted fabric composed of a number of longitudinally extending chains each of which is composed of alternating series of loops, each series of loops being composed 10 of a locking thread and a locked thread, the said locking thread of one pair at the junction between adjacent series of loops of the same chain, being looped around the locked thread of the pair of threads forming the 15 adjacent series of loops and thence, together with its companion thread extending transversely and forming a series of loops of another chain.

9. A knitted fabric composed of a number 20 of longitudinally extending chains each

of which is composed of alternating series of loops, each series of loops being composed of a locking thread and a locked thread, the said locking thread of one series of loops, at the junction therebetween and the adjacent 25 series of loops of the same chain, being looped around the neck of a loop formed by the locked thread of such adjacent series of loops, said locking thread and the locked thread of the same pair thence extending 30 transversely to an adjacent chain and looped to form a series of loops of another chain.

In testimony of which invention, I have hereunto set my hand, at Philadelphia, on this 28th day of October, 1914.

FRANK CLEWLEY.
